UNITED STATES PATENT OFFICE.

ISAAC E. PALMER, OF MIDDLETOWN, CONNECTICUT.

CLAMP FOR TENTERING-MACHINES.

SPECIFICATION forming part of Letters Patent No. 587,754, dated August 10, 1897.

Application filed October 21, 1896. Serial No. 609,502. (No model.)

To all whom it may concern:

Be it known that I, ISAAC E. PALMER, of Middletown, in the county of Middlesex and State of Connecticut, have invented a new and 5 useful Improvement in Clamps for Tentering-Machines, of which the following is a specification.

The object of my invention is to provide an improvement in that class of machines 10 in which the tentering-clamps are located around the periphery of the tentering-wheel and are opened and closed at the proper times for receiving, retaining, and permitting the withdrawal of the selvage edge of the material being tentered or stretched.

A further object is to provide a tentering-clamp which will be very simple in construction, positive in operation, and in which the 15 spring-actuated jaw has a rigid gripping-surface and the rigid jaw provided with an adjustable seat, whereby the material may be firmly and positively held against slipping when the clamp is closed and may be readily withdrawn from the clamp when the clamp 25 is open.

A practical embodiment of my invention is represented in the accompanying drawings, in which—

Figure 1 represents a side view of a tentering-wheel, showing a number of the tentering-clamps secured in position thereon, it being understood that the clamps are intended to extend entirely around the periphery of the wheel. Fig. 2 is a vertical central section 35 through the wheel on the line 2 2 of Fig. 1. Fig. 3 is a vertical central section through the clamp when in its closed or gripping position, and Fig. 4 is a side view of the clamp in its open position.

The tentering-wheel is denoted by A, and it is mounted in suitable supports B, the support on the side of the wheel on which the clamps are secured being provided with a pair of stationary cams b b', which cams are the 40 one adapted to open the clamps for the reception of the selvage edge of the cloth and the other adapted to open the clamps for the release of the cloth.

The clamp as a whole is denoted by C and 45 its rigid jaw by c and the spring-actuated movable jaw by c'. The rigid jaw c is pro-

vided with a downwardly-extended portion c², which is adapted to be secured to the inner face of the wheel A at its periphery. The rigid jaw c is bifurcated, and between its branches is pivoted the swinging jaw c' upon a suitable pivot-pin c³. The rigid jaw c is provided with an adjustable seat c⁴, which is hinged at its forward end at c⁵ to the upper end of the rigid jaw c. The rear or free end 55 of the said seat is bifurcated, and between its branches passes the swinging jaw c'. The swinging jaw c' is provided with a pair of shoulders c⁶, which are adapted to slide along the under surface of the adjustable seat c⁴ 60 and raise and lower the same as the jaw c' is opened or closed. The swinging jaw c' is further provided with a suitable retaining-pin c⁷ for still further guiding the seat c⁴ in its swinging movements. The free end of 65 the swinging jaw c' is provided with a rigid gripping-head c⁸, which is preferably provided with a series of laterally-extending teeth c⁹, which project rearwardly, the said teeth serving to still further secure the selvage edge of the material in position against 70 the adjustable seat c⁴ when the clamp is closed. The swinging jaw c' is held yieldingly closed by means of a suitable spring D, which in the present instance is of coiled 75 form, wound around the pivot c³ and having one end engaged with the downwardly-projecting portion c² of the fixed jaw c and its other end pressing against the swinging jaw c'. The swinging jaw c' is provided with a 80 suitable tailpiece c¹⁰, which is adapted to be engaged by the cams b b' at the side of the wall A for opening the said jaw against the tension of the spring D at the proper times.

In operation the clamps C are located close 85 together around the periphery of the wheel A, and as the wheel is rotated they are first opened by the fixed cam b', for instance, for receiving the selvage edge of the cloth, and after the clamps have passed part of a revolution they are engaged by the other fixed cam for opening them for allowing the selvage edge of the material to be withdrawn.

It is evident that slight changes might be resorted to in the construction and arrangement of the several parts without departing 90 from the spirit and scope of my invention.

Hence I do not wish to limit myself strictly to the structure herein set forth, but

What I claim is—

A clamp for tentering-machines, comprising a rigid jaw, an adjustable seat pivoted to the said jaw, and a swinging jaw pivoted to the rigid jaw, the head of the swinging jaw

being provided with a gripping-face for engaging the adjustable seat when the clamp is closed, substantially as set forth.

ISAAC E. PALMER.
